PUMP CONTROL SYSTEM

Theodore C. M. Mauch, Indianapolis, Ind., assignor to S. Morgan Smith Company, York, Pa., a corporation of Pennsylvania

Application June 18, 1946, Serial No. 677,607

8 Claims. (Cl. 103—40)

1

This invention relates to new and useful improvements in control mechanisms for turbine driven machines, and more particularly to mechanisms for controlling operation of check valves in the discharge lines of turbine driven centrifugal pumps.

Valves of this type generally are employed in centrifugal pump installations where it is necessary to check reverse flow through the pump, for example, where centrifugal pumps are used to deliver water against pressure to a main or to a storage reservoir. Such centrifugal pump installations quite often are driven by means of steam turbines and if for any reason the steam pressure supply to the turbine should fail or drop materially and reverse flow set in then the centrifugal pump acts as a turbine to drive the steam turbine in the reverse direction with probable resulting damage and injury to the turbine.

It is highly desirable therefore to prevent reverse flow through the pump by closing the check valve to prevent reverse flow, and the object of the present invention is to provide a novel control mechanism or system which is operable automatically under predetermined conditions to close the check valve in the pump discharge line before reverse flow sets in.

Another object of the invention is to provide a novel control mechanism of the stated character which is operable in response to variations in the pressure of the steam supplied to the turbine to drive the same.

A further object of the invention is to provide a novel control having the features and characteristics set forth which is highly effective and foolproof in operation and use.

These and other objects of the invention and the various features and details of the construction and operation thereof are hereinafter fully set forth and described with reference to the accompanying drawing in which the single figure is a diagrammatic showing of a steam turbine driven centrifugal pump installation embodying a check valve control mechanism in accordance with the present invention.

Referring now more particularly to the drawing, reference numeral 1 designates a centrifugal pump to which are connected the customary intake and discharge lines 2 and 3, respectively. Connected in the pump discharge line 3 adjacent the pump 1 is a valve 4 which is operable under certain conditions, hereinafter more fully explained, to close the discharge line 3 and thereby preclude reverse flow through the pump 1. Preferably the valve 4 is of the well-known four-

2

way hydraulic piston operated type controlled, in the present instance, by means of a pilot valve 5 which is actuated by means of a solenoid device 6.

5 In the illustrated embodiment of the invention, the construction and arrangement of the check valve 4 is such that when the solenoid 6 is energized the said valve 4 is fully open to permit flow through the line 3, and upon de-energization of the solenoid 6 said valve 4 is closed to preclude flow through the discharge line 3. Electrical conductors 7 and 8 lead from suitable line conductors 9 and 10, respectively, to the solenoid device 6 and energization of the latter to operate pilot valve 5, and thereby the check valve 4 in the pump discharge line 3, is effected by means of a pressure operated electric switch 11 which is connected in series with the said conductors 7 and 8. In the illustrated embodiment of the present invention the contacts of the switch 11 normally are held in closed circuit relation as shown, by means of a pressure responsive bellows or diaphragm device 12.

10 The centrifugal pump 1 is rotationally driven by means of a conventional type steam turbine 13 which is coupled to the shaft 14 of said pump through suitable reduction gearing. The turbine 13 in turn is rotationally driven by steam supplied to said turbine 13 at a predetermined pressure through a steam line 15 having a suitable control valve 16 therein, and according to the present invention the bellows or diaphragm 12 is adapted to be operated to control the switch 11 in response to a predetermined steam pressure condition existing at any time in the line 15 between the turbine 13 and the control valve 16 therefor.

15 To this end, therefore, the interior of the bellows or diaphragm 12 is connected by means of a pipe or tube 17 to the interior of a chamber 18 at the bottom thereof, and an intermediate portion of this pipe or tube 17 is suitably coiled, for example, as indicated, to provide a cooling coil or condenser 19 between the chamber 18 and the bellows or diaphragm 12 of the switch 11. 20 A similar pipe or tube 20 leads from the interior of the chamber 18 at the top thereof and has its other end connected into the steam line 15 between the turbine 13 and its control valve 16, while an intake pipe or tube 21, having an inwardly opening one-way check valve 22 therein, leads into the chamber 18 at the top thereof and has its other end open to the atmosphere as shown.

25 The bellows or diaphragm 12 of the switch 11 thus is subjected to the pressure of the steam

in the steam line 15 leading to the turbine 13 between the latter and the control valve 16, and the bellows of diaphragm 12 is constructed and calibrated to effect opening of the switch 11 to break the electrical circuit to the solenoid 6 when the said steam pressure in line 15 falls below a predetermined value as hereinafter described.

The cooling coil or condenser 19 provided in the pipe or tube 17 functions to condense steam flowing through the pipe or tube 17 from the line 15 toward the bellows or diaphragm 12 and the switch 11 so that the steam does not reach these mechanisms and they are not subjected to the high temperature of the steam and heated thereby to an extent that may cause damage or disrupt the calibration or settings thereof and of other devices and controls that may be mounted upon the same control panel or board as the switch 11. Excess condensate formed in the coil or condenser 19 drains or flows into the chamber 18.

In the case of a complete failure or shut-down of the steam supply in the line 15 to the turbine 13, the pressure in the line 15 between the valve 16 and turbine 13 frequently is reduced to a value below atmospheric pressure thereby producing a suction force in the pipe 20 and chamber 18 which tends to withdraw the condensate from the chamber 18 and the pipe 17. It is highly desirable that provision be made to prevent withdrawal of the water condensate from the chamber 18 and the tube or pipe 17 in such cases and, in the present instance, this is accomplished by the provision of the aforesaid intake pipe or tube 21 and one-way check valve 22 which operate to admit atmospheric air into the chamber 18 so that the suction force in the tube 20 and chamber 18 merely draws air from the atmosphere inwardly through the pipe 21 and chamber 18 to the turbine 13 without disturbing the water condensate in said chamber 18 and the pipe or tube 17.

In operation of the system and assuming, for purposes of illustration only, that the normal operating steam pressure in the supply line 15 to the turbine 13 is 150 pounds gauge and that the switch actuating bellows or diaphragm 12 is constructed and arranged to hold the switch 11 closed under such normal operating conditions and to open said switch, in the event that the steam pressure in the line 15 falls below say, 80 pounds gauge, it will be apparent from the foregoing description that upon failure of the steam pressure or upon shut down through operation of the throttle 16, the steam pressure supply to the turbine in the line 15 almost instantly will fall below the 80 pounds setting of the bellows or diaphragm 12, causing the latter to open the switch 11 thereby deenergizing the solenoid 6 to actuate the pilot valve 5 and cause the check valve 4 to close and prevent reverse flow from the line 3 through the centrifugal pump 1. In addition, it is to be noted that in starting operation of the pump system, as the steam throttle 16 is opened to warm the turbine 13 the initial pressure will be very low but as the turbine speed is brought up to approach the normal pumping speed a pressure of approximately 80 pounds gauge is reached thereby causing the bellows or diaphragm 12 to close the switch 11 resulting in energization of the solenoid 6 and consequent operation of the pilot valve 5 to open the check valve 4.

From the foregoing it will be seen that the present invention provides a novel control mech-

anism or system for steam turbine driven centrifugal pump installations which is operable automatically under predetermined conditions to close the check valve in the pump discharge line before reverse flow sets in. The invention also provides a control mechanism of the stated character which operates in response to variations in the pressure in the steam supply to the turbine to drive the same, and which is highly effective and foolproof in operation and use.

While a particular embodiment of the present invention has been illustrated and described herein, it is not intended to limit the invention to such disclosure, and changes and modifications may be made therein and thereto within the scope of the claims.

I claim:

1. In a pumping system, a centrifugal pump having inlet and discharge pipes, a steam turbine operatively connected to said pump to drive the same, a steam supply line to said turbine, a check valve in the pump discharge pipe normally open during operation of the pumping system, valve operating mechanism including pressure responsive means constructed and arranged to effect closing of said check valve upon the pressure in said steam supply line falling below a predetermined value, a pressure line connecting from said steam supply line to said pressure responsive means, a cooling coil in said pressure line for condensing steam therein, a closed chamber in said pressure line intermediate the steam supply line and said cooling coil to receive excess condensate from the latter, and means connecting the interior of said chamber to the atmosphere operable in the event of sub-atmospheric pressure in the steam supply line to prevent withdrawal of the condensate from said chamber and cooling coil.
2. In a pumping system, a centrifugal pump having inlet and discharge pipes, a steam turbine operatively connected to said pump to drive the same, a steam supply line to said turbine, a throttle valve in said line to control the supply of steam to said turbine, a check valve in the pump discharge pipe normally open during operation of the pumping system, valve operating mechanism including pressure responsive means constructed and arranged to effect closing of said check valve upon the pressure in said steam line between the throttle and the turbine falling below a predetermined value, and a pressure line connecting to said pressure responsive means from said steam supply line between the turbine and the throttle therein.
3. In a pumping system, a centrifugal pump having inlet and discharge pipes, a steam turbine operatively connected to said pump to drive the same, a steam supply line to said turbine, a throttle valve in said line to control the supply of steam to said turbine, a check valve in the pump discharge pipe normally open during operation of the pumping system, valve operating mechanism including pressure responsive means constructed and arranged to effect closing of said check valve upon the pressure in said steam line between the throttle and the turbine falling below a predetermined value, a pressure line connecting to said pressure responsive means from said steam supply line between the turbine and the throttle therein, a cooling coil in said pressure line for condensing steam therein, a closed chamber in said pressure line intermediate the steam supply line and said cooling coil to receive excess condensate from the latter, and means connecting

the interior of said chamber to the atmosphere operable in the event of sub-atmospheric pressure in the steam supply line to prevent withdrawal of the condensate from said chamber and cooling coil.

4. In a pumping system, a centrifugal pump having inlet and discharge pipes, a steam turbine operatively connected to said pump to drive the same, a steam supply line to said turbine, a check valve in the pump discharge pipe normally open during operation of the pumping system, means to operate said valve including a solenoid, an electrical circuit to energize said solenoid, normally closed switch means in said electrical circuit, pressure responsive means to actuate said switch means constructed and arranged to open said switch means and thereby close said check valve upon the pressure in said steam line falling below a predetermined value.

5. In a pumping system, a centrifugal pump having inlet and discharge pipes, a steam turbine operatively connected to said pump to drive the same, a steam supply line to said turbine, a check valve in the pump discharge pipe normally open during operation of the pumping system, means to operate said valve including a solenoid, an electrical circuit to energize said solenoid, normally closed switch means in said electrical circuit, pressure responsive means to actuate said switch means, a pressure line connecting from said pressure responsive means to said steam supply line and subjecting said pressure responsive means to the pressure in said steam line, said pressure responsive means being constructed and arranged to open said switch means and thereby close said check valve upon the pressure in said steam line falling below a predetermined pressure.

6. In a pumping system, a centrifugal pump having inlet and discharge pipes, a steam turbine operatively connected to said pump to drive the same, a steam supply line to said turbine, a check valve in the pump discharge pipe normally open during operation of the pumping system, means to operate said valve including a solenoid, an electrical circuit to energize said solenoid, normally closed switch means in said electrical circuit, pressure responsive means to actuate said switch means, a pressure line connecting from said pressure responsive means to said steam supply line and subjecting said pressure responsive means to the pressure in said steam line, said pressure responsive means being constructed and arranged to open said switch means and thereby close said check valve upon the pressure in said steam line falling below a predetermined pressure, a cooling coil in said pressure line for condensing steam therein, a closed chamber in said pressure line intermediate said cooling coil and the steam supply line to receive excess condensate from said cooling coil, and means connecting the interior of said chamber to the atmosphere operable in the event of sub-atmospheric pressure in the steam supply line to prevent withdrawal of the condensate from said chamber and cooling coil.

7. In a pumping system, a centrifugal pump having inlet and discharge pipes, a steam turbine operatively connected to said pump to drive the same, a steam supply line to said turbine, a throttle valve in said line to control the supply of steam to said turbine, a check valve in the pump discharge pipe normally open during operation of the pumping system, means to operate said valve including a solenoid, an electrical circuit to energize said solenoid, normally closed switch means in said electrical circuit, pressure responsive means to actuate said switch means, a pressure line connecting from said pressure responsive means to said steam supply line between the turbine and throttle to subject said pressure responsive means to the pressure in said steam line, said pressure responsive means being constructed and arranged to open said switch means and thereby close said check valve upon the pressure in said steam line falling below a predetermined pressure.

8. In a pumping system, a centrifugal pump having inlet and discharge pipes, a steam turbine operatively connected to said pump to drive the same, a steam supply line to said turbine, a throttle valve in said line to control the supply of steam to said turbine, a check valve in the pump discharge pipe normally open during operation of the pumping system, means to operate 25 said valve including a solenoid, an electrical circuit to energize said solenoid, normally closed switch means in said electrical circuit, pressure responsive means to actuate said switch means, 30 a pressure line connecting from said pressure responsive means to said steam supply line between the turbine and throttle to subject said pressure responsive means to the pressure in said steam line, said pressure responsive means being constructed and arranged to open said switch 35 means and thereby close said check valve upon the pressure in said steam line falling below a predetermined pressure, a cooling coil in said pressure line for condensing steam therein, a 40 closed chamber in said pressure line intermediate said cooling coil and the steam supply line to receive excess condensate from said cooling coil, and means connecting the interior of said chamber to the atmosphere operable in the event of 45 sub-atmospheric pressure in the steam supply line to prevent withdrawal of the condensate 50 from said chamber and cooling coil.
